Patented Feb. 14, 1928.

UNITED STATES PATENT OFFICE.

EDWARD G. BARNETT, OF CONCORDVILLE, PENNSYLVANIA.

BASKET CARRIER.

Application filed November 21, 1925. Serial No. 70,537.

This invention relates to a novel carrier for baskets or other receptacles, and contemplates a device that may be readily carried from place to place or temporarily attached to a support while in use.

To that end the invention contemplates a simple, practical and reliable frame construction of maximum rigidity and strength, thereby providing a carrier which is practical and efficient in use, and simple and economical to make. In that connection it is proposed to provide a carrier or holder for baskets or other receptacles particularly adapted for use in the picking of mushrooms where one basket is used to receive stems, or foreign matter that might cling to the mushroom itself, while the other receptacle is used for the marketable mushrooms.

In addition to the foregoing general object, it is proposed to provide a carrier that can be readily made from strip-metal of suitable gauge and weight to carry the load of mushrooms, and yet not be too heavy to be cumbersome and awkward in handling.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings in which

Figure 1 is a perspective view of the present invention.

Figure 2 is a side elevation illustrating the application of the invention.

Figure 3 is a top plan view of the construction shown in Figure 2 without the baskets or other containers in position.

Similar reference characters designate corresponding parts throughout the several figures of the drawings.

By reference to the drawing it will be observed that the present novel carrier device includes a handle or bail portion designated generally as A, and the opposite receptacle holding cradles B and C. In other words, it is proposed to provide a carrier having a central handle or bail with the receptacle carrying elements on opposite sides thereof, while one of said elements has associated therewith the supporting means D.

A preferred manner of making the carrier is illustrated in Figure 1 wherein the

central bail or handle portion A is formed by a strip of metal bent into substantially inverted U-shaped formation, thereby to provide the hand grip 1 and the depending end members 2, each of which are laterally offset to form the receptacle supporting arms 3 which provide the bottom of the basket or receptacle carrier B, while the free ends of said offset arms 3 are upturned as indicated at 4, thereby providing guards for holding the baskets in place.

As clearly shown in the drawings, the lower parts of the side members 2 are formed at right angles to the downturned end portions of the hand grip 1 thereby to provide flat inner side walls for the basket receiving cradles. One face of the arms 2 has secured thereto, by means of the rivets 5 or their equivalent, the attaching portions 6 of the angularly formed cradle forming member C. These members include the horizontal wall 7 which terminates in the inverted U-shaped end portions 8 which form hanger-hooks that constitute the supporting members D.

In use the device is intended to hold one or more receptacles for the purpose of transporting the same to and from the point of use, and also keeping the receptacles off the ground and close to the point of picking of the mushrooms from the beds. As shown in Figure 1 the cradle portion B may hold a large basket for receiving the marketable mushrooms while the cradle C may receive a small basket for receiving the culs, stems, and other foreign matter while the carrier is hung on the side of one of the beds as indicated in Figure 2. The present device has been found of great convenience in the picking of mushrooms, berries, and other vegetables and fruit. Not only does the present carrier provide for conveniently holding the two baskets readily available and in proper position, but also enables one workman to readily transport a carrier in each hand thereby increasing his carrying capacity without much additional effort whereas heretofore it is customary to make separate trips to handle the marketable mushrooms and the waste material, thereby saving much time in the picking and handling of the vegetables or fruit.

Without further description it is thought that the features and advantages of the invention will be readily apparent to those skilled in the art, and it will of course be

understood that changes in the form, proportion and minor details of construction may be resorted to, without departing from the spirit of the invention and scope of the 5 appended claims.

I claim:

1. A receptacle holder and carrier of the class described comprising a central member formed to provide a carrying bail and having oppositely offset receptacle supporting members providing receptacle seats at opposite sides of the bail, the members on one side of said central supporting member being formed integrally therewith.

2. A device of the class described comprising a central supporting bail of substantially inverted U-shaped formation, arms laterally offset in opposite directions and carried by the lower end of said bail member, a pair of said arms being formed integrally with said supporting bail, each pair of said arms at one side of the bail constituting a receptacle support whereby the device may support a plurality of receptacles side by side.

In testimony whereof I hereunto affix my 25 signature.

EDWARD G. BARNETT.
